UNITED STATES PATENT OFFICE.

JOSEPH W. SCHLOSS, OF NEW YORK, N. Y.

BUTTON.

No. 918,775.

Specification of Letters Patent.

Patented April 20, 1909.

Application filed October 6, 1908. Serial No. 456,365.

To all whom it may concern:

Be it known that I, JOSEPH W. SCHLOSS, a citizen of the United States, residing at the city of New York, in the borough of Manhattan and State of New York, have invented 5 certain new and useful Improvements in Buttons, of which the following is a full, clear, and exact description.

My invention relates to soft or flexible buttons of the sort which are used on ladies' 10 cloaks or garments, and which are made in varying sizes and shapes.

In my Patent No. 866,817, issued September 24, 1907, I have set forth a form of button 15 which is very soft and spongy in its texture, in accordance with the trade requirements in this class of goods. This button is formed by taking a disk of felt or other spongy but coherent substance and knitting, crocheting or braiding a fabric cover or envelop thereon. This button proves very satisfactory in use, except that the soft spongy character makes it rather less efficient as a fastening device than a button of the ordinary sort. 20 This is particularly true where the button is used on ladies' cloaks as a fastening for the "frog" or braided loop which is sometimes employed in lieu of a button hole.

The principal object of the present invention is to provide a button which has substantially 30 all the spongy characteristics as set forth in my prior patent, but which is more efficient as a fastening device and which is supported slightly offset or elevated away 35 from the surface of the garment to which it is secured, so as to give more room for the frog or button hole with which it co-operates.

A further object of the invention is to provide a soft, spongy button which will not be 40 so completely distorted or drawn out of shape by the strains to which it is subjected in the holding action as to fail to hold the buttonhole or frog with which it may be engaged, or to lose its ornamental appearance.

45 A further object of the invention is to provide a fastening of greater security than heretofore by which the button is attached to the supporting garment.

A still further object of the invention is to 50 provide a button core or body as an article of manufacture which is adapted to be sold or furnished to purchasers who may desire to supply covers to suit their own particular tastes or purposes. As will later appear, I 55 provide an envelop which can be made separately and afterward applied to the button,

in place of my previous construction, where the button was employed as a former in the crocheting process.

With these and various other objects in 60 view, my invention consists in the features of construction as hereinafter set forth and claimed.

In the drawings: Figure 1 is a side view showing the separate parts of a button core 65 or body embodying the principles of my invention. Fig. 2 shows a completed button core or body. Fig. 3 shows the braided or fabric envelop. Fig. 4 is a sectional view of the completed button. Fig. 5 is a perspective view of a completed button. Fig. 6 is a 70 sectional view showing a slightly modified core.

1 designates a disk of spongy but coherent substance such as felt which is conveniently 75 made by punching out a circular portion from a flat sheet of material of proper thickness. While these disks are very soft, flexible and spongy, it is evident that they have, nevertheless, a definite shape to which they 80 return after deformation in the manner of felt and analogous coherent, spongy substances generally. These characteristics of having great softness and flexibility, and at the same time having a definite shape under 85 normal conditions, are regarded as the important ones for the button core or filler employed by me. Since the disks are all stamped from sheets of felt of uniform texture and thickness, it is evident that they 90 are exactly alike in all matters of form, size, texture, density and weight, as required. Upon this core I assemble a disk 2, made of hard pasteboard, metal or other rigid material which has preferably, although not 95 necessarily, a diameter about that of the felt core or body 1. This disk has a central hole or aperture 3.

4 designates a loop made of a wire or sheet metal strip or similar material somewhat in 100 the form of a paper fastener, and having prongs 5 which may be inserted through the hole of the disk and preferably through a small additional metal washer 6. The washer 6 is important in practice when the 105 disk 2 is of cardboard or the like, as it prevents the prongs 5 from tearing out through the cardboard disk and furnishes substantially as great security in the fastening as if the disk itself were made of metal. If the 110 prongs are bent over in the manner shown in Fig. 4, and the disk assembled and secured

adjacent to the felt core 1, it is evident that a complete button core or body is provided in the manner shown in Fig. 2. This button core is very spongy, but has a convenient shank 4 which will, moreover, maintain the button slightly offset or elevated from the surface of the garment to which it is attached. The disk 2 may be glued or pasted to the core 1 if desired, but this is not necessary except as a means of associating the parts of the core until the fabric cover or envelop is applied. The fabric cover 7 may be knitted, crocheted or braided in the cup shaped form shown in Fig. 3 entirely separate from the core or body of the button. Afterward the cover may be drawn over the core and the edges gathered around shank 4 by taking a few stitches 8 therein, so as to completely inclose the core and produce a completed button of the outline shown in Figs. 4 and 5. The pasteboard or other disk 2 is in this way entirely covered up, but the shank 4 is left protruding through any distance required, by which the button adroitly serves all its utilitarian purposes, as well as possessing the soft, spongy character required by the trade in this class of goods.

In place of a rigid metallic shank 4 a tuft

of fabric 9 (see Fig. 6) may be employed in exactly the same relation. In this case, the button would be sewed on the garment through the fabric tuft in place of through the loop of the metallic fastening device.

What I claim, is:

1. As an article of manufacture, a button core of spongy but coherent substance having a rigid disk associated therewith on the rear face thereof, a fastening device engaged between said disk and core and projecting from the center of said disk, and a fabric cover, said cover directly enveloping said core and disk and depending solely thereon for its support and shape.

2. A button having a core of spongy but coherent substance and a disk of rigid material associated therewith on the rear face thereof, and a fabric cover, said cover directly enveloping said core and disk and depending solely thereon for its support and shape.

In witness whereof, I subscribe my signature, in the presence of two witnesses.

JOSEPH W. SCHLOSS.
